ORIN A. HANFORD, OF ROCHESTER, NEW YORK, ASSIGNOR TO EMPIRE MACHINE COMPANY, OF PORTLAND, MAINE, A CORPORATION OF MAINE.

ELECTRICALLY-CONTROLLED BLOWING-HEAD FOR GLASS-BLOWING MACHINES.

1,123,523.

Specification of Letters Patent.

Patented Jan. 5, 1915.

Application filed November 4, 1910. Serial No. 590,693.

To all whom it may concern:

Be it known that I, ORIN A. HANFORD, a citizen of the United States of America, and a resident of Rochester, New York, have invented certain new and useful Improvements in Electrically-Controlled Blowing-Heads for Glass-Blowing Machines, of which the following is a specification.

My invention relates to certain improvements in the parts of what is termed the blowing head of glass blowing machines whereby such parts are electrically controlled.

Heretofore it has been the practice so far as known to me to so construct the chuck forming part of such a head, that the chuck was either closed upon the blow-pipe manually after the introduction of the blow-pipe therein, necessitating a special movement of the operator for this purpose, or else the blow-pipe has been caught by the chuck, due to the force with which it is inserted therein, this jarring the gather and being incompatible with the requirements of the fine work. By one feature of my invention I prevent this, as the insertion of the blow-pipe into the chuck closes an electrical circuit by which the chuck jaws are actuated to grasp the blow-pipe. The chuck is further advantageous in that a very flexible drive for the blow-pipe is provided and one which in spite of the inequalities and irregularities existing between the blow-pipes permits the gathering ends thereof to be properly positioned over the molds without straining the parts.

The second feature of my invention, namely the electrically actuated air valve, is particularly desirable in machines in which the air valve is relatively movable in respect to the part by which its opening and closing is controlled, for instance such as described in another application filed by me on this 27th day of October, 1909, serially numbered 524,994, in that the use of complicated transmitting mechanism is dispensed with and the weight of the valve actuating parts reduced. This I accomplish by providing an electrically actuated air valve, the energizing circuit of which is closed and opened at a proper time either manually or by the blowing machine during its operation.

My invention consists in the construction, combination and arrangement of the parts

by which the above results are obtained, as will be hereinafter more fully described and claimed.

Referring to the accompanying drawings in which corresponding parts are designated by corresponding marks of reference: Figure 1 is a longitudinal vertical section through a blowing head constructed in accordance with this invention. Fig. 2 is a horizontal section thereof on line X²—X² of Fig. 1. Fig. 3 is an inverted horizontal section on line X³—X³ of Fig. 1. Fig. 4 is an enlarged longitudinal sectional view through the stem of the chuck. Fig. 5 is a side elevation partly broken away of the plunger and clutch for the chuck. Fig. 6 is a similar view of Fig. 5 taken at right angles thereto. Fig. 7 is an enlarged section through the valve cylinder of the air valve.

The blowhead forming the subject matter of this application may be mounted in any approved manner but as shown it is carried on the upper part of a frame composed of the rods A which pass through the chuck casing A'. This casing has in front of the rods A a longitudinal bushed bearing a in which is mounted the tubular stem B, which at its lower end is united to the shell C of the blow-pipe chuck by the screw joint b, which permits the ready assemblage of the parts. The chuck shell is tubular and contains within the interior thereof the cores of magnets D, D', energized by the coils d, d' respectively, the winding of the magnets being such that unlike poles of the magnets are presented to each other. The pole ends of the magnets are so shaped as to form between them radial guide ways d² extending longitudinally of the axis of the chuck, in which on each side of such axis are contained magnetic plungers E, E', etc., the construction of the parts being such that upon the energization of the magnets the plungers are drawn toward the axis of the chuck, the ends of the plungers being rounded to bear upon the end of the blow-pipe (shown dotted in Fig. 1) which may be inserted within the central recess left between the magnetic cores within the chuck shell. By reason of the fact that a plurality of plungers are used upon each side of the axis, the one located above the other, an intimate contact is obtained between the plungers and the blow-pipe in spite of any irregularity in the shape of the latter, by which a greater

driving grip is obtained. For the purpose of permitting the ready insertion of a blow-pipe within such chuck the lower end of the shell thereof is partly closed by a plate c' having a bell mouth c^2 serving as a guide for the blow-pipe to properly position it in respect to the central hole or recess in the magnets. The chuck stem B projects through the chuck casing A' and has thereon a pinion F gearing with a driver F' upon the end of the shaft F² mounted in the frame formed by the rods A and to which shaft motion may be imparted in any suitable manner. As thus constructed it will be seen that the blow-pipe chuck will be rotated by means of the shaft F².

For the purpose of conveying current to the coils d, d' of the electromagnetic chuck, the shell C has upon the upper surface thereof 20 of two collector rings G, G' upon which brushes g, g' carried in a laterally projecting ear from the casing, respectively bear. The collector ring G' is directly connected to one end of the coils d and d' by means of a flexible conductor g² and the ring G is connected to the other end of the coils by means of an automatic switch which will now be described.

Mounted centrally within the stem B of 30 the chuck, and guided for longitudinal movement therein, by a plug H in the base thereof and by a reduced central bore t' at the top of the stem is a tubular plunger I, the plunger being normally depressed by 35 means of a spring i contained in the bore. The plug H has a collar J upon its upper end and insulated from the body of the plug by the insulating material j, the said collar having projecting upwardly from one side 40 thereof a standard j² upon which is pivoted at j³ the contact arm K having a forked bell crank k which embraces a striker pin i⁴, upon the side of the plunger I. The upper end of this contact arm plays between a stop 45 ear j⁴ formed upon the standard j² and a contact ear j⁵ formed upon the plate j⁵ carried upon and insulated from the top of the standard j². The body of the plug H has longitudinal bores therein, bushed with insulating material L, in which are contained 50 conducting pins l, l', which when the chuck is assembled respectively contact with spring m and m' mounted in the shell C, the spring m being connected to the ring G by the wire n while the pin l is connected by the conductor o with the insulating plate j⁵. The ring J is connected by the wire o' with the pin l' and the spring m' is connected by the wire n' with that end of the coils d, d' which is 55 not connected to the collector G'. The lower end of the plug H is recessed to receive and take a gasket h' surrounding the lower end of the plunger I and held in place by the washer h².

60 65 With the parts thus assembled it will be

seen that upon the introduction of the blow-pipe in the bell mouth c² and through the central bore of the magnets the extreme end thereof will come into simultaneous contact with the gasket h' and end of the plunger I 70 and that as the blow-pipe is shoved into place the plunger will be lifted and will through the pin i⁴ rock the lever K to throw the upper end thereof into contact with the contact stop j⁶ on the insulated plate j⁵, thus closing the work-circuit from brush g to brush g' as follows; brush g, ring G, wire n, contact spring m, pin l, wire o, plate j⁵, contact j⁶, contact lever K, ring J, wire o', pin l', spring m', wire n', coils d' and d, wire g², 75 collector ring G' and brush g', thus energizing the magnets and causing the plungers E, E', etc., to be drawn against and drive the blow-pipe. To permit the removal of the blow-pipe after the blowing the circuit 80 external to that herein described may be broken in any approved manner thus de-energizing the magnets to release the pressure of the plungers on the blow-pipe to release the grasp thereon.

Inasmuch as the end of the plunger I is held in intimate contact with the end of the blow-pipe by the push spring i, it will be seen that the plunger will follow in its longitudinal movement any corresponding 90 movement that may be given to the blow-pipe and to permit slight movement of the blow-pipe without effecting the contact between the contact stop j⁶ and the contact lever K, a limited amount of play is left 95 between the pin i⁴ and the bell crank k of the contact lever, whereby this movement of the plunger is permitted. This necessitates that means be employed to hold the contact arm K in its two extreme positions until it 100 is moved by the plunger and this is provided in the form of a spring P, having its one end mounted in the standard j² and its opposite end mounted in the contact lever K, the tension of the spring in the position 105 shown in Figs. 4 and 5 being to hold the contact lever against its back stop j⁴, while after the lever has been forcibly moved over a certain distance toward the contact stop j⁶, the spring will be shifted as shown in dotted lines in these figures to hold the arm 110 forcibly against the last named contact. This spring therefore provides for throwing the switch arm in either direction and serves to hold it in one or the other of its 115 extreme positions until it is forcibly removed, therefrom.

A hollow combined air and valve box Q is mounted in the head, being secured above the chuck casing by the rods A which pass 120 therethrough and contains in its base axially to the chuck a stuffing box R into which the upper end of the tubular stem B of the chuck projects. The upper end of the stuffing box receives a valve well R' provided

with a valve seat R^2 provided with an eccentrically situated port r' . Within the valve well is rotatably contained a valve cylinder S provided with an eccentrically situated port s' , the valve cylinder being held against the valve seat by a coil spring S' , one end of which is secured to the valve cylinder and the other end to the plate T mounted over the cylinder and rigidly carried in the air box, the function of the spring being not only to hold the valve cylinder upon its seat but also to hold it in its normal angular position, which is shown at Fig. 7.

15 Two pairs of vertical electromagnets V are mounted in the air box chamber Q around the valve well and have their like poles connected by pole pieces V' which are concentric in respect to the axis of rotation of the valve cylinder, which latter carries an armature V^2 mounted between the pole pieces and adapted to be drawn by the pull thereof when energized into a position to cause the ports r' and s' in the valve seat 20 and valve cylinder to register, thus permitting air which may be introduced into the valve chamber through the induction port q to enter the tubular plunger and thus flow into the blow-pipe. The external circuit of 25 these magnets may be completed from the binding posts u' through a switch worked automatically as a function of a machine or manually as may be desired and the ports r' and s' are extended on their contiguous ends 30 by V-shaped slots r^2 and s^2 respectively disposed at a considerable angle to the diameter passing through the ports, thereby producing a gradual increasing in the area of the air passage as the valve is turned to a 35 greater extent, which is desirable in an air valve for a glass blowing machine. The top of the air box Q carries a dial disk W , adapted to be clamped in any desired position by the clamp nut W' and provided 40 with an outwardly projecting pin w adapted by contacting with the armature V^2 to arrest the rotation of the latter at any desired point, thereby determining the extent 45 to which the air valve shall be opened. A

handle w' may be provided to set this dial 50 plate in the desired position.

Having thus described my invention what I claim and desire to secure by Letters Patent is:—

1. An electromagnetic chuck for glass 55 blowing machines, comprising electromagnets and a series of superimposed independently movable plungers actuated thereby and adapted to grasp the blow-pipe.

2. An electromagnetic chuck for glass 60 blowing machines, comprising electromagnets, the polar extensions of which form guide chambers and a series of superimposed, independently movable plungers contained in the said chambers and adapted to 65 grasp the blow-pipe.

3. An electromagnetic chuck for glass 70 blowing machines, the combination with a chuck shell, of electromagnets contained in the said shell, the polar projections of which form guide chambers, a series of superimposed independently movable plungers contained in the said chambers and adapted to grasp the blow-pipe, means for rotating the said tubular shell and means for conducting 75 an electric current to the said electromagnets.

4. The combination in an electromagnetic chuck for glass blowing machines, of rotating electromagnets, plungers actuated 80 thereby and adapted to grasp the blow-pipe, and an electric switch adapted to complete the circuit through the said magnets upon the insertion of the blow-pipe in the chuck.

5. In an electromagnetic chuck for glass 85 blowing machines, the combination with electromagnets having a central recess to receive the blow-pipe, means for rotating the magnets, an armature for the said magnets adapted to grasp the blow-pipe, a plunger 90 mounted in the chuck and adapted to be moved by the blow-pipe and a switch adapted to be thrown by the plunger to complete the circuit of the electromagnets.
